CLAIM

The ornamental design of a dessert cup, as shown and described.

DESCRIPTION

FIG. 1 is a perspective view of a dessert cup showing my new design;

FIG. 2 is a top plan view thereof;

FIG. 3 is a side elevation view thereof. The other side views are identical to this view;

FIG. 4 is a side elevational view of an alternate embodiment of FIG. 1. The other side views are identical to this view; and,

FIG. 5 is a top plan view of the alternate embodiment shown in FIG. 4.

The bottom view is planar and unornamented.
